(57) **CLAIM**

The ornamental design for an interchangeable/wearable hinged audio device, as shown and described.

DESCRIPTION

FIG. 1 is a front view of an interchangeable/wearable hinged audio device showing the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof.

FIG. 8 is a perspective view thereof showing the glasses frame in an unassembled position;

FIG. 9 is a partial enlarge view of FIG. 7; and,

FIG. 10 is a partial enlarge view of FIG. 8.

The broken lines shown in the drawings illustrate portions of the interchangeable/wearable hinged audio device that form no part of the claimed design.

1 Claim, 9 Drawing Sheets

FIG. 9
